UNITED STATES PATENT OFFICE.

WILLIAM F. CONKLIN, OF TARENTUM, PENNSYLVANIA.

AUTOMATIC BRAKE MECHANISM.

1,162,573.

Specification of Letters Patent. Patented Nov. 30, 1915.

Application filed June 3, 1914. Serial No. 842,807.

To all whom it may concern:

Be it known that I, WILLIAM F. CONKLIN, a citizen of the United States, residing at Tarentum, in the county of Allegheny and 5 State of Pennsylvania, have invented certain new and useful Improvements in Automatic Brake Mechanism, of which the following is a specification.

My invention consists of an improvement 10 in automatic brake mechanism, and particularly relates to means for applying braking pressure upon a train of rolls or the like.

The particular object in view is to interpose frictional resistance to the rotation of 15 one of the parts of a train of rolls, or the like, to absorb back lash, prevent racing, and to continuously provide a retarding friction at all times of a substantially uniform degree, and at the same time prevent the use 20 of unnecessary friction and resulting waste of power.

While the invention is adapted to any mechanism in which the conditions are similar and in which it is desired to provide such 25 braking action or retardation, the improvement is particularly applicable to control the rolls of a rolling mill.

It is a well-known fact among rolling mill operators, especially sheet rollers, that a 30 momentary stop or shock occurs when a sheet of hot steel is passing between the rolls, because of an uncontrolled back lash, lost motion, or other inequality in operation. This objection is completely overcome by 35 my invention.

In the drawings, showing such adaptation, Figure 1 is a view in sectional elevation, indicated by the line I. I. of Fig. 2, 40 showing the improvement as applied to a roll member. Fig. 2 is a plan view of Fig. 1. Fig. 3 is an end view in elevation, corresponding to the construction shown in Figs. 1 and 2.

In the drawings, the numeral 2 represents 45 a roll or journal or any cylindrical member coupled by its neck and the usual coupling box, not shown, with the roll or rolls of a train.

In the particular adaptation of the invention, the member 2 is shown as an actual roll, which may be a used roll of a train, or 50 especially designed, as preferred, it being understood however that the particular construction of the cylindrical member 2 is not 55 essential, and the invention is applicable to such a member, whether truly cylindrical

or otherwise, due to wear upon its surface. This statement is made because of the facility of utilizing used or worn rolls in connection with the braking mechanism, for 60 economy.

At each side of the roll member 2 are casings 3, 3, the numerals generally indicating the rectangular box structures adapted to contain the operative mechanism, and which are mounted upon the usual foundation bed plate members 4, 4, of a rolling mill.

The casings 3 are rigidly braced and connected by suitable framing caps 5 above and the main housing member 6 below, between 70 which at the end portions of the structure are interposed the roll bearings 7, for the necks of the roll member 2. The housing members 6 extend from one bed plate 4 to the other, and also upwardly at each side of 75 the necks of roll member 3, providing for the mounting of the bearing brasses 7.

The friction casings 3 are mounted upon plates 26 which extend across from one bed plate 6 to the other and are connected thereto by bolts 27 engaging slots 28 therein. By 80 this means the housings 6 may be spaced apart as desired to provide for varying lengths of roll members 2.

The roll or journal member 2 is engaged 85 at one or both sides by braking shoe elements 8 which as shown are blocks of wood or other suitable material, and which are forced as worn against the cylindrical surface endwise of the grain. The friction blocks 8 are within the housing 3 and behind the blocks is the pusher or follower 9 slidably mounted within the housing.

A plunger 10 is provided interfitting with follower 9 and a temper screw 11 is threaded into a nut 12 thereof. Between the plunger 10 and follower 9 is interposed a cushioning spring 13 for compensation of inequalities, etc., in the roll or for providing 100 a degree of resilience between the positively actuated nut and the friction blocks, and to keep a constant tension on blocks 8.

A removable plate 3^a closes the friction block space, and may be removed when it is necessary to renew the blocks, and then screwed down tight by bolts and nuts, as 105 shown.

Screw 11 extends outwardly through the end of the casing 3 or an end plate 3^a thereon, and is provided with a gear, as a worm wheel 14, such construction being in duplicate for exerting pressure throughout the 110

length of the roll 2, the plungers 10 being preferably connected by a cross bar 15, thus providing plungers at each side. Worm wheels 14 are in mesh with a worm 16 operating to actuate them together, and upon the upper end of the worm shaft is rotatably mounted a drum 17 having a pawl 18 engaging a ratchet wheel 19 secured to the worm shaft and operable to rotate the shaft in one direction but to run free in the reverse direction.

A cable 20 is wound on the drum 17 and is passed around sheaves 21, 22, supported in bracket 23 and is provided with an actuating counterweight 24.

The steady pull of the counterweight operates to exert turning pressure on the worm gearing and screw 11, tending to constantly feed the friction blocks 8 inwardly against the roll 2 as they wear away, thus maintaining a uniform braking pressure at all times. When desired, the weight may be raised and the cable rewound on the drum 17 by merely reversing it freely of the ratchet mechanism, when the weight will again exert its force to continue the screw feed of the friction blocks. These may be renewed as worn, and the device will thus maintain any desired degree of frictional pressure on the roll, depending on the weight of element 24.

As shown the construction is the same at each side of the roll, but it will be understood that it may be employed at one side or two, and with a single or double screw and worm wheel, according to the friction desired.

A water pan 25 is arranged below the roll member 2 and provides water into which is immersed the roll and its necks for a considerable depth, thereby avoiding undue heating due to the friction of the blocks 8.

The device may be applied to any suitable kind of apparatus in which it is desirable to effect braking pressure on a rotatable cylindrical body, and it will be understood that it may be changed or varied to suit

different conditions of use or otherwise by the skilled mechanic, but that all such changes are to be considered as within the scope of the following claims.

What I claim is:

1. The combination with a rotatable cylindrical member, of friction shoes, a screw adapted to press the shoes against the cylindrical member, a resilient member between the shoes and screw, and a gravitating member geared with the screw whereby to exert a constant torque thereon, substantially as described.

2. The combination with a rotatable cylindrical member, of friction shoes, a follower, a screw adapted to press the follower and friction shoes toward said member, gearing for said screw, and a weight operatively connected with said gearing.

3. The combination with a rotatable cylindrical member, of friction shoes, a follower, a screw, a plunger operated thereby and adapted to exert pressure against the follower, a worm wheel on said screw, a worm having a drum, and a cable engaging said drum provided with guiding mechanism and a weight.

4. Friction mechanism of the class described consisting of a casing, friction members therein, a follower therefor, a plunger, a spring between the follower and plunger, a screw for the follower provided with a worm wheel, a worm therefor having a shaft provided with a drum having ratchet connection with the shaft, a supporting bracket having guiding sheaves, and a flexible element connected with the drum passing around said sheaves and provided with a terminal counterweight.

In testimony whereof I hereunto affix my signature in the presence of two witnesses.

WILLIAM F. CONKLIN.
